United States Patent Office

Des. 219,517

Patented Dec. 22, 1970

219,517

PLAQUE

George M. Wallace, 64 Clinton St.,
Paterson, N.J. 07522

Filed Nov. 13, 1969, Ser. No. 20,065

Term of patent 14 years

Int. Cl. D11—99

U.S. Cl. D29—23

FIG. 1 is a front elevational view of a plaque showing my new design;

FIG. 2 is a side elevational view thereof;

FIG. 3 is a bottom plan view; and

FIG. 4 is a top plan view.

I claim:

The ornamental design for a plaque, showing my new design.
